**BATTERY OPERATED TOY ADAPTED TO
SIMULATE A DENTAL DRILL**

Adolph E. Goldfarb, 6927 Eagle Ave.,
North Hollywood, Calif.

Filed July 22, 1959, Ser. No. 828,845
3 Claims. (Cl. 46—39)

This invention relates to a battery operated toy adapted to simulate a dental drill.

One of the objects of this invention is to provide a battery operated toy or novelty which presents the illusion that same is a dental drill and produces a sound simulating that of a dental drill in operation.

Another object of this invention is to provide a toy which may be used by a child to pretend that he is simulating a dentist in drilling a tooth.

Another object of this invention is to provide means for varying the frequency and intensity of the sound thereby creating the illusion of actual drilling.

Other objects will become apparent as this description progresses.

In the drawings:

FIGURE 1 is a side elevational view of the simulated dental drill with a portion thereof in section.

FIGURE 2 is a top plan view.

FIGURE 3 is a longitudinal cross-sectional view showing particularly the sound producing means.

FIGURE 4 is an enlarged view of the contact switch, and

FIGURE 5 is a schematic view of the circuit.

The shape of the device is best shown in FIGURES 1 and 2, and comprises a housing generally indicated at 1 preferably molded in its entirety of plastic material. The housing includes a centrally positioned rectangular shaped chamber generally indicated at 2, a forwardly extending neck 3 which inclines upwardly and which has a simulated dental bit 4 and drill 5 formed thereon. Extending rearwardly from the chamber 2 is a bullet shaped chamber generally indicated at 6 which supports a small dry cell battery. The sound producing means, presently to be described, is contained in the central chamber 2 which is closed by a removable side cover 7 secured by any conventional means. The drill 5 does not rotate but is merely intended to simulate the conventional structure.

A conventional dry cell battery 9 is housed within the chamber 6. Extending longitudinally of the chamber 6 is a metal strip 12, the terminal portion 13 of which is arranged to contact the bottom of the dry cell battery 9 constituting the negative terminal of the same. A conductor wire 14 is connected to the strip 12 and to the coil winding of electromagnet 16. Said electromagnet is supported on a metal strip 17 which is riveted by an eyelet as at 18 to the wall of the housing of chamber 2, the electromagnet 16 being insulated from the strip 17 by an insulating washer 19.

The strip 17 angles upwardly and is bent vertically and then horizontally as shown in FIGURE 3. Riveted to the horizontal arm 21 in stacked relationship is a resilient armature 22 having one end overhanging the electromagnet 16, an insulating washer 23, a flat bar member 24 and an insulating washer 26. The rivet 27 affords an electrical connection with the arm 21 and armature 22. The bar member 24 is insulated from rivet 27 and is provided at the face end with a contact element 28 to which is soldered a conductor wire 29 leading from the opposite end of the coil winding of the electromagnet.

A conductor strip 31 is riveted to the inner wall of the housing of chamber 2 and extends longitudinally thereof. One end portion 25 of strip 31 is bent to afford a contact with the positive pole of the dry cell. The other end

of the strip 31 is bent to form an offset arm 32 overlying the rivet 27. A button 33 passing through an aperture in the wall of the housing is operatively engaged against the arm 32. Under normal inoperative conditions the arm 32 is spaced from and out of contact with the rivet 27.

When the button 33 is depressed and contact between arm 32 and rivet 27 is established current will flow from the positive pole of the battery 10 through conductor 31, arm 32, rivet 27, armature 22, contact 28, conductor 29, 10 the coil winding of the magnet 16, conductors 14 and 12 and finally to the negative pole of the dry cell 9. The electromagnet 16 is thereby energized and draws the armature 22 downwardly breaking contact with contact 28. This results in a break in the circuit and deenergization 15 of the electromagnet 16 which causes release of the armature 22 which thereupon reestablishes contact with contact 28 and reenergization of the electromagnet. This cycle is repeated so long as the button 33 is depressed producing a high pitched buzzing sound simulating 20 that of a dental drill.

The frequency and intensity of the sound may be varied depending on the pressure applied to button 33. When the pressure on button 33 is changed, the distance between armature 22 and the electromagnet 16 is also 25 changed, therefore varying the frequency of the sound. This is due to the fact that the buzzer is supported on strip 17 which is mounted by an eyelet as at 18, with the rest of strip 17 floating and acting as a pivot point so that any pressure on button 33 will not only make electrical 30 contact but will push the mechanism, pivoted at 18 down, thus changing the distance between the armature and the electromagnet.

It will be understood that various changes and modifications may be made from the foregoing without departing from the spirit and scope of the appended claims.

I claim:

1. A toy simulating a dental drill comprising a housing and a neck extending forwardly thereof, a simulated dental bit secured to the front end of said neck, a de- 40 pressible member secured to the top of said housing, a supporting member having a lower and an upper portion, means for securing one end only of the lower portion of the supporting member to the bottom of said housing inside said housing with the balance of said supporting member spaced from the bottom of said housing, an electromagnet mounted on said lower portion, an armature mounted on said upper portion to extend over the top of said electromagnet, a battery supported in said housing and in electrical circuit with said electromagnet, said de- 45 pressible member when depressed closing the electrical circuit to operate said electromagnet and armature to produce a buzzing sound simulating that of a dental drill in operation, said de-pressible member depressing said sup- 50 porting member at the end opposite where said electromagnet is mounted to change the distance between the electro-magnet and the armature.

2. A toy described in claim 1 in which the frequency and intensity of the sound is varied by varying the pressure on the de-pressible member.

3. A toy simulating a dental drill comprising a housing and a neck extending forwardly thereof, a simulated dental bit secured to the front end of said neck, a manually de- 65 pressible member secured to the top of said housing, a supporting strip secured only at one end to the bottom of the said housing inside said housing with the balance of said strip spaced from the bottom of the housing and with the opposite end of the strip extending upwardly thereof inside said housing, an electromagnet mounted on said strip adjacent the bottom end thereof, an armature mounted on said strip adjacent the opposite end of said strip so that the armature extends over the electromagnet,

a battery supported in said housing rearwardly of said electro-magnet and in electrical circuit with said electro-magnet, said depressible member when depressed closing the electrical circuit to operate said electromagnet and armature to produce a buzzing sound simulating that of a dental drill in operation, said depressible member being depressible to varying degrees to cause said supporting strip to give and move downwardly towards the bottom of the housing to change the distance between the elec-

tromagnet and the armature to vary the frequency of the sound.
